AUTOMATIC FIRE EXTINGUISHER

Filed June 10, 1944

UNITED STATES PATENT OFFICE

2,397,761

AUTOMATIC FIRE EXTINGUISHER

Donald C. Soper, Los Angeles, Calif.

Application June 10, 1944, Serial No. 539,613

5 Claims. (Cl. 169—2)

My invention relates to automatic fire extinguishers for moving picture projectors, and among the objects of my invention are:

First, to provide a fire extinguisher adapted to be readily installed on a conventional motion picture projector, and which is designed to introduce a fire extinguishing fluid into the projector mechanism in the event that the film thereon should catch fire.

Second, to provide a fire extinguisher of this class wherein the fire extinguishing fluid is not under pressure until the extinguisher is caused to operate, but instead pressure is applied to the fire extinguishing fluid simultaneously with discharge of the fluid.

Third, to provide a fire extinguisher of this class which, by reason of the fact that the fire extinguishing fluid is under no pressure when not in operation, is capable of remaining idle for long periods of time without loss of fluid.

Fourth, to provide a fire extinguisher of this class which in no manner interferes with the operation and maintenance of the moving picture projector.

Further objects and advantages of my invention will appear as the specification proceeds, reference being directed to the accompanying drawing, in which:

Fig. 1 is a fragmentary front elevational view of a moving picture projector with my fire extinguisher shown thereon.

Fig. 2 is an enlarged fragmentary view of the projector, partially in side elevation and partially in section, showing my fire extinguisher in position.

Fig. 3 is a sectional view through 3—3 of Fig. 2 taken through the housing of the projector mechanism and showing the relation of the fusible link and discharge valve of my fire extinguisher, the discharge valve and adjacent parts being shown in section, whereas the fusible link and its associated parts are in elevation.

Fig. 4 is a fragmentary rear elevational view of the projector, with my fire extinguisher shown partially in section and partially in elevation, the section being taken substantially along the line 4—4 of Fig. 2.

Fig. 5 is an enlarged fragmentary sectional view through 5—5 of Fig. 3, showing the relationship of the valve and the fusible link.

My fire extinguisher is adapted to be installed on any of the conventional moving picture projectors and such projectors include a housing 1 indicated fragmentarily in the drawing. The housing is provided with an upward extension or

5 a separate adapter housing 2 which is mounted on top of the housing 1, and supports a reel case 3 which contains a reel on which is wound film 4. The film 4 feeds downwardly through a slot in the periphery of the reel case and into the adapter housing 2. Here guide sprockets 5 engage the film. The film continues downwardly into the housing 1 and around an upper drive sprocket 6 and into a guide 7 forming a part of 10 the intermittent mechanism used to position the film, a frame at a time, in registry with the projection apparatus (not shown).
 15 My fire extinguisher is mounted on the rear side of the reel case and is adapted to discharge a fire extinguishing fluid into the housing 1 in the event that the film should catch fire. A reservoir 11 in the form of a vertical tube closed at its ends, is secured by attachment straps 12 at its upper and lower ends to the rear side of 20 the reel case 3. A flexible tube 13 extends from the lower end of the reservoir and is provided with a fitting 14 so that it may be secured in a convenient wall of the housing 1 or adapter housing 2. In the illustration the fitting is shown as 25 mounted in the adapter housing. The fitting 14 forms a valve seat 15 which is closed by a conically shaped valve member 16 located within the adapter housing. The valve member is mounted on one arm of a lever 17 which extends laterally 30 from the valve, then vertically along the side wall of the adapter housing, and is fulcrumed intermediate its ends on a pin 18. The other or remaining end of the lever 17 is attached to a cable 19 which is threaded through a guide 20 likewise supported from the side wall of the adapter 35 housing 2. The cable 19 is secured to a fusible link 21 positioned over the loop of film passing around the drive sprocket 5 and into the guide 7 so as to be fully exposed to the heat generated 40 by the film should it catch fire. In this connection it should be noted that virtually the only portion of the film in any danger from fire, is that portion which is passing through the intermittent mechanism and subjected to the heat incidental to the focused beam of light directed 45 against the film.

The remaining end of the fusible link is connected to an arm 22 which projects laterally through the adapter housing 2 and is attached to 50 one arm of a bell crank lever 23 journaled intermediate its ends by a bracket 24 provided at the lower end of the reservoir 11. The other or horizontal arm of the bell crank 23 is joined to a connecting rod 25 which extends upwardly along the side of the reservoir 11, and is pivotally connected

to a latch lever 26. The latch lever is journalled intermediate its ends by an upstanding yoke 27 provided at the upper end of the reservoir 11.

Within the reservoir 11 is a plunger 28 to which is attached a stem 29 extending upwardly through a guide formed in the upper end of the reservoir. The protruding portion of the stem 29 is provided with a notch 30 adapted to be engaged by the latch lever 26 so as to hold the plunger 28 in its upper position within the reservoir 11. The upper end of the plunger stem is provided with a cross head 31 to the extremities of which are springs 32. The springs 32 extend downwardly along the sides of the reservoir 11 and are attached to lugs 33 projecting laterally from an anchor band 34 secured to the lower portion of the reservoir 11.

Operation of the fire extinguisher is as follows: The reservoir 11 and flexible tube or conduit 13 are filled with a fire extinguishing fluid such as carbon tetrachloride. The plunger 28 is held in its upper position by the latch lever 26, and the latch lever is in turn held in position by the mechanical linkage comprising the connecting rod 25, bell crank lever 23 and arm 22 which is joined to one end of the fusible link 21. The other end of the fusible link is so joined to the lever 17 that the downward thrust of the plunger stem 29 on the latch lever 26 is transmitted through the mechanical linkage and the fusible link to exert a force holding the valve closed. Adjustment of the parts is such that this condition is obtained without the plunger 28 exerting any force on the fire extinguishing fluid so that there is only a nominal internal pressure against the valve member 16 as long as the fusible link is intact.

Upon being heated beyond its fusing point, the fusible link 21 parts, thereby releasing the latch lever 26 and permitting the springs 32 to exert a downward force on the plunger 28. At the same time, the valve is released so that the fire extinguishing fluid now under pressure is forced out of the tube 13 into the adapter housing 2 and housing 1. The movement of the valve member 16 may be limited so that when it moves to its open position it tends to act as a deflecting member to spray the fire extinguishing fluid and thereby increase its effectiveness.

Many other embodiments of the invention may be resorted to without departing from the spirit of the invention:

I claim:

1. The combination with a moving picture projector having a film handling mechanism and a housing therefor, of a fire extinguisher, comprising: a reservoir adapted to contain a fire extinguishing fluid mounted in proximity to said housing; a flexible conduit communicating between said reservoir and said housing; a valve within said housing initially closing said conduit, means for applying pressure to the fire extinguishing fluid within said reservoir, a latch for restraining said means whereby said fluid is substantially pressure free, a mechanical linkage communicating between said latch and said valve through a wall of said housing and holding said valve in its initial or sealing position, and a fusible link in-

corporated in said mechanical linkage and located in said housing in proximity to the film therein, whereby upon fusing of said link said mechanical linkage releases said latch.

2. The combination with a moving picture projector having a film handling mechanism and a housing therefor, of a fire extinguisher, comprising: a reservoir adapted to contain a fire extinguishing fluid mounted in proximity to said housing, a flexible conduit communicating between said reservoir and said housing, a valve within said housing initially closing said conduit, a piston slidable in said reservoir, springs for urging said piston against said fluid, a latch for restraining said springs whereby said fluid is substantially pressure free, a mechanical linkage communicating between said latch and said valve through a wall of said housing and holding said valve in its initial or sealing position, and a fusible link forming an element of said mechanical linkage and located in proximity to the film handled by said mechanism to fuse upon ignition of said film, thereby to free said valve and release said latch.

3. A fire extinguisher comprising: a reservoir for fire extinguishing fluid, a flexible conduit leading therefrom to a point of application, a valve closing said conduit at said point of application, means for applying pressure to the fluid in said reservoir, a device for restraining said means whereby said fluid is substantially pressure free, mechanical linkage extending between said device and a point adjacent said valve, and a fusible element connected with said valve and with said linkage to hold said valve closed and said fluid free of pressure while said fusible element is intact.

4. A fire extinguisher comprising: a reservoir for fire extinguishing fluid, a conduit leading therefrom to a point of application, a valve closing said conduit at said point of application, a piston slidable in said reservoir, springs for urging said piston against said fluid, a latch for restraining said springs, mechanical linkage including a fusible element extending between said latch and said valve to hold said valve closed and said fluid free of pressure while said fusible element is intact.

5. The combination with a moving picture projector having a film handling mechanism and a housing therefor, of a fire extinguisher comprising: a reservoir adapted to contain a fire extinguishing material and mounted in proximity to said housing; a flexible conduit communicating between said reservoir and said housing; a valve within said housing for closing said conduit; a spring-actuated instrumentality for applying pressure to the contents of said reservoir; means connecting said instrumentality and said valve to hold said valve in a closed position and to restrain said spring-actuated instrumentality whereby said fluid is substantially pressure free; and a fusible link forming an element of said means and exposed to the film handled by said mechanism, said means adapted upon fusing of said link to release said valve and said instrumentality.

DONALD C. SOPER.
